SERPOOHIE HAGOPIAN, OF SAN FRANCISCO, CALIFORNIA

COMBINED AWNING AND SCREEN

Application filed November 25, 1927. Serial No. 235,713.

This invention relates to improvements in combined awnings and screens, and has particular reference to the employment of a shading means in conjunction with an adjustable window screen.

The principal object of the invention is to provide a device of the character described which is simple in construction, economical to manufacture and which can be applied to 10 the conventional type of adjustable screen without materially altering the construction of the same.

Other objects and advantages will be apparent during the course of the following 15 description.

In the accompanying drawings forming a part of this specification, and in which like numerals are employed to designate like parts throughout the same,

20 Figure 1 is a front elevation of my device with a portion of the awning being broken away to more clearly illustrate the awning supporting means,

25 Figure 2 is a top plan view of the means for supporting the awning,

Figure 3 is a transverse vertical section through the device on the line 3—3 of Figure 1,

30 Figure 4 is an end view of the apparatus, Figure 5 is a transverse vertical section through the screen sections, and

Figure 6 is a transverse vertical section through the device on the line 6—6 of Figure 1.

35 In certain localities even in the presence of inclement weather conditions such as rain or fog, it is often desired to retain the conventional adjustable screen in the window aperture. However, when the screen is in position the fog and rain often enter the room, resulting in a soiling of the draperies adjacent the window or a spotting of the woodwork.

40 Furthermore, in balmy weather the entrance of the sun through the screen is often annoying and it is necessary to pull the inside shade to shield the occupant from the sun, thus obstructing the view of the occupant.

45 In the present invention I have endeavored

to overcome the necessity of removing the screen from the window opening, and the further annoyance of having the fog or rain enter the room, by combining with an adjustable screen an awning that will permit ventilation and will protect the interior of the room from the referred to elements, and to further provide a device which can be readily secured to the conventional type of adjustable screen without materially altering the 55 construction of the same, and at the same time provide a device that will readily accommodate itself to varying sizes of window openings.

In the accompanying drawings wherein 60 for the purpose of illustration is shown a preferred embodiment of my invention the numeral 7 designates one screen section, while the numeral 8 refers to a second screen section which is slidably mounted in the first 65 mentioned section as indicated at 9 and 10. These screen sections are of conventional construction and by virtue of the sliding arrangement are adjustable to varying widths of window openings. The sill of 70 the window in the present instance is indicated by the numeral 10.

Hingedly connected as at 11 to the end rail 12 of the section 7, is an end strip 13, which strip has secured thereto and at right angles 75 to a cross bar 14.

As illustrated to advantage in Figure 4, the strip 13 and bar 14 have secured thereto a portion of canvas 15 which serves as one-half 80 of the awning, the canvas being secured in the 85 rear to the screen section 7.

From this construction it will be obvious 90 that as the screen section is slidably manipulated with relation to the section 8, the canvas portion will be free to move with said section 7.

It is to be further noted that a conventional 95 collapsible bracket 16 is employed to connect the end rail 12 and the strip 13 so that this section of the awning may be readily moved to an operative position for its desired shading function.

Referring now to the means for supporting the other canvas portion which combines with the canvas portion 15 to present a unique 100

shading arrangement, the numeral 17 designates a pair of cross arms which have secured to their free extremities a cross bar 18 defining a frame for retaining a second canvas portion 19. It is to be noted that the opposite extremities of the arms 17 are hingedly connected as at 20 to the screen section 8.

5 A collapsible bracket 21 serves to connect one of the arms 17 to an end rail 21 of the screen section 8 and functions to permit the canvas portion 19 to be collapsed.

10 In case it is not desired to extend the awning outside of the window, it is only necessary to invert the screen and the awning will 15 extend inside of the room.

15 From the foregoing description considered in connection with the accompanying drawing, it will be evident that I have devised a simply constructed device consisting of a 20 combined awning and screen that is applicable to window apertures of varying widths, which can be easily installed and a device which will effectively prevent the entrance of the elements when it is positioned in the 25 window sill and held in its conventional place.

It is to be understood that the form of my invention herewith shown and described is to 30 be taken as a preferred example of the same and that various changes relative to the shape, size, material and arrangement of parts may be resorted to without departing from the spirit of the invention or the scope of the subjoined claim.

25 Having thus described my invention, I claim:—

30 A combined awning and screen comprising a pair of slidably connected screen sections, an awning construction for said screen sections, said awning construction comprising a 40 pair of frames, each hingedly connected to its respective hinged section, a covering for each of said frames, and collapsible brackets for 45 each of said awning sections for connecting said awning sections to said screen sections.

45 In testimony whereof I affix my signature.
SERPOOHIE HAGOPIAN.
